UNITED STATES PATENT OFFICE.

JOHN J. McGUCKIN, OF BROOKLYN, NEW YORK, ASSIGNOR TO LOUIS SCHWAB, DOING BUSINESS AS STEVENS & COMPANY, OF NEW YORK, N. Y.

SCREW EXTRACTOR.

Application filed July 2, 1924. Serial No. 723,798.

To all whom it may concern:

Be it known that I, JOHN J. McGUCKIN, a citizen of the United States, residing at Brooklyn, Kings County, New York, have invented certain new and useful Improvements in Screw Extractors, of which the following is a specification.

My invention relates to screw extractors, which are intended to remove screw elements which cannot be grasped by the head in the ordinary way, the extractor being applied by forcing it into a hole drilled into the screw to be removed.

The objects of my invention are to so construct the portion of the extractor which engages with the screw to be extracted that it will be properly guided in the process of insertion, and will tend to hug to its seat during the movement of extraction, but may be readily released by a direct pull with or without a slight retrograde revolution.

In the drawings Fig. 1 is an elevation of my improved tool; Fig. 2 is an end view looking to the right on Fig. 1; and Fig. 3 is an end view looking to the left on Fig. 1.

Similar reference numerals designate similar parts in all the figures.

The shank 1 of the tool is provided with a suitable portion as 2, whereby it may be gripped by a turning tool; and it is provided at its other end with a preferably reduced portion 3 of substantially the same diameter as the hole into which the extractor is to be inserted, so that the cylindrical part 3 may make a snug fit in said hole. A socket or annular groove 4 is formed around this reduced portion 3, leaving a terminal 5 with substantially the same diameter as the portion 3.

On the body of the portion 3 are formed ribs 6, preferably having comparatively acute-angled outer edges, and being carried from the recess 4 back along the reduced portion 3 for a considerable distance with very slight lateral deflection. In the drawings I have illustrated the tool as being provided with four such ribs, but it will be readily understood that the number may be varied as is desirable to accommodate the tool to the particular work in view.

The tool is used by first drilling a hole, of substantially the same diameter as the ter-

5 minal 5 and the portion 3, into the body of the screw element to be extracted, inserting the terminal 5 in the hole, and then driving 55 the tool down thereinto, the ribs 6 directly overlap the edges of the hole so that they gouge out seats in the metal of the screw element to receive themselves as the tool is driven home, the cuttings or scraps of metal 60 gouged out by the ribs being forced before them and finding accommodation in the scrap receiving recess 4 without clogging the tool.

As the tool forces itself home, the increasing twist of the ribs will cause them to follow their channels in the screw element; so that a very firm connection will be established between the tool and the screw to be extracted. The ribs 6 having a left-hand 70 pitch, tend to hug the tool down into its socket during the left-hand movement of unseating an ordinary right-hand screw. And yet the wedging of the extractor into the socket in the screw, will not be such 75 that any considerable degree of, if any, right-hand rotation will be necessary to unseat it from the screw. In fact, a sharp blow upon the screw element, with a hammer or the like, will usually suffice to drive it 80 off of the extractor, the deflection of the flanges being so slight that the tool will not jam against such a movement of separation.

By means of my improvement I secure a 85 tool which can be simply and effectually connected with a screw element to be extracted, by driving it into a cylindrical socket, which will positively and effectively grip the element to be extracted, and may be 90 readily separated therefrom by direct longitudinal movement.

It will be understood that I have illustrated and described a typical form of the embodiment of my improvement and that 95 the details of construction may be varied, as by the use of mechanical equivalents, without departing from the spirit of my invention as claimed.

Having thus described my invention, what 100 I claim and desire to secure by Letters Patent of the United States is:—

A screw extractor, for screws having plain surfaced longitudinal cylindrical sockets

therein, provided with a cylindrical terminal portion of substantially the same diameter as the socket into which it is to be forced, said portion having an annular scrap-receiving recess therein and longitudinal cutting ribs thereupon above said recess, the ends of which are adapted directly to overlap the

edge of the socket and to gouge seats for themselves in the wall of the socket receiving the tool, the ribs having a slight lateral deflection only, compared with the deflection of the screw's thread, from the longitudinal axis of the tool. 10

JOHN J. McGUCKIN.
